UNITED STATES PATENT OFFICE.

LOUIS H. CROOK, OF WASHINGTON, DISTRICT OF COLUMBIA, ASSIGNOR OF ONE-HALF
TO HERMAN JAKOBSSON, OF TAKOMA PARK, MARYLAND.

NONGROUNDED TRANSMISSION LINE.

Application filed October 21, 1926. Serial No. 143,207.

My invention relates to electric transmission lines in general but more particularly to lines of high voltage and has for its object to arrange the lines in such a manner that all accidents from shocks, caused by contact with bare conductors, are avoided.

Another object resides in the fact that interference between two separate lines is prevented by the application of the present invention so that telephone, telegraph or radio messages may be sent freely without interruption, or that radio broadcasting or reception may be conducted without interference from other electric lines. In this manner a radio instrument, for example, may be operated close to the ignition line on an automobile.

These and other advantages are obtained thru the use of the present invention.

Considering an ordinary air line, such as a trolley line for instance, in which the circuit from an electric power source includes a wire carried on poles, as one conductor, and the ground constitutes the other conductor. If now the wire should break and contact with a body standing on the ground, said body will experience a shock when the current passes therethru, and this shock may be fatal as many thousands of volts may be carried over the wire.

Taking now the same example and supposing that one of the conductors, the ground, could be slit open and wrapped around the other conductor, the wire, but without touching the latter, then an ideal condition would prevail, where it would be perfectly safe to touch the ground or negative conductor even if the positive conductor or wire should be broken and contact with the negative conductor, because the latter protects the former so that the positive conductor cannot be reached from the outside.

Now the present invention aims at creating this ideal condition, practical solutions of which being described in the following description and illustrated in the accompanying drawing,

Figure 1 is a diagrammatic, perspective view of a non-grounded electric line forming the subject matter of the present invention;

Figure 2, a diagrammatic view and partial section of an ignition system for an automobile;

Figure 3, a plan view of a detail, and

Figure 4, a diagrammatic view and partial section of a similar arrangement for an X-ray tube.

Referring first to Fig. 1 on the drawing, this shows a general application of the invention to any type of electric transmission line, and reference numeral 10 represents a chamber enclosed on all sides and preferably lined with a good conductor such as copper or other metal. Numeral 11 is another similarly constructed and lined chamber. Instead of lining the chambers they may be made entirely of metal. A copper lined or metal tube 12, connects the two chambers. A conductor or transmission wire 13, is enclosed in the tube, but completely insulated as at 14 from its walls as well as from the chamber walls. Any doors or windows in the chambers should be wired and no other openings permitted of any large size except 75 holes so small that no leakage or induced effects are possible.

The primary or sending chamber contains any kind of electric generating mechanism, such as a generator, dynamo, battery, radio 80 transmission set, high tension coil set for X-ray work or auto-transmission set or the like, which in the following will be designated as the "generator" and in Fig. 1 is denoted by reference numeral 15. This generator is placed in the middle of the chamber so as to be free from the walls or else insulated from them. In case an external motor, such as a hydraulic or steam turbine, is used for supplying mechanical energy to 90 the "generator" this energy may be transmitted thru a shaft 6 into the chamber 10, care being taken that the shaft is properly insulated.

One of the conductors 16, the negative one 95 for instance, is connected with the wall or lining of the chamber as at 17 and it should be noted that this is not "grounding" as commonly understood, because the current will not pass thru to the earth but it corresponds 100 in operation to the so called ground. The positive conductor 18 is connected to one end of the wire or cable 13. In the special case of radio-telegraphy this wire would serve as 105 antenna, while the metallic lining of the chamber 10 and the tube 12 would correspond to the "ground". The receiving instrument 19 which may be a radio receiving set, is also positioned in the middle of the secondary chamber 11 or insulated from its 110

walls to which it, however, is connected as at 20 by a negative conductor 21, while a positive conductor 22 connects with the wire 13. By this arrangement, electric current can 5 thus be sent from the "generator" 15, thru conductors and wire 18, 13 and 22 to the instrument 19 and back to the generator thru conductor 21, the lining of the chamber 11, tube 12, chamber 10 and the conductor 17. 10 There is absolutely no necessity for a "ground" with the earth since all the electric energy is confined within the space enclosed by the negative, metallic conductor, that is to say, the lining of the chambers 10, 11 and 15 the tube 12.

In Fig. 2 is shown the application of my invention to a Ford coil. As before, the primary chamber 25 and the tube 26 are metallic or copper lined and a battery 27, properly insulated from the walls but electrically connected therewith by a conductor 28, as at 29, is placed in this chamber. The positive conductor 30 connects the battery 27 with the coil 31, which with its negative conductor 32, thru the commutator 33, connects with the lining or wall of the chamber 25. Both the coil 31 and the commutator 33 are suitably insulated from the chamber walls.

The coil 31, thru the positive conductor 34, connects with one end of the wire 35 which runs thru the tube 26 but is insulated therefrom as at 36. The tube or its lining is secured to the metallic part of the spark plug 37, making a completely enclosed space 35 from the chamber to the spark plug with the exception of the opening at the lower end of the spark plug over which a metallic screen or plate is stretched as at 38. The wire 35 runs thru the porcelain or dielectric 40 39 and ends with a spark point 40 between which and the screen 38 the spark gap is formed. The spark plug is preferably insulated as at 41 from the cylinder walls.

It should be particularly noted that the 45 battery 27 is enclosed in the chamber, so that the complete electric energy disturbance is internal, in the apparatus.

High tension is now produced by the coil 50 between the wire 35 and the metal lining 26, and when the gas passes thru the screen 38 from the combustion chamber it will be ignited by a spark at the gap 38-40. All 55 changes of electric energy are internal. The action of the spark plug is accordingly the same as in ordinary arrangements but has no effect on wireless or other electric apparatus that happens to be in its vicinity.

In Fig. 3 the invention is shown as used 60 for an X-ray tube. In this case a metal box 45 forming a closed chamber is also used. It contains the usual high voltage mechanism including generator with coils 46 insulated from the chamber walls. The generator is actuated from any mechanical 65 source of power, externally of the box, thru

a drive shaft 47 properly insulated from the chamber walls or made of insulating material. The X-ray tube 48 is practically in the same box being placed in the tubular extension 49 which is also metallic and closed 70 at its end 53 and has a downwardly directed, funnel shaped aperture 50, over which the usual metallic screen 51 is stretched. The tube 48 is supported in the metallic extension 49 by insulations 52. 75

A negative lead 54 from the high voltage coils of the generator 46 connects with the walls of the box 45 and the positive lead 55 running thru the insulations 56 in the metallic extension 49, connects with one end of 80 the X-ray tube 48, while the lead 57 connects the other end of the X-ray tube 48 with the metallic tube 49.

By this arrangement the current runs from the generator coil at 46 over the insulated 85 wire 55 to the X-ray tube 48 and returns to the generator thru the lead 57, the metallic walls of the extension tube and the box 45 and the negative lead 54.

The radiant energy emanating from the 90 surface of the thus excited X-ray tube passes out thru the inverted funnel 50 to the body to be treated. Since, however, the wire 55 is completely enclosed and only the box or metallic tube 49 can be reached from the 95 outside, no shock or other electric effect will be felt by either physician or patient when touching the metallic box or tube. Or in other words, an electric circuit cannot be formed between any external points of the 100 apparatus; that is to say the apparatus has what is known amongst physicists as an external "equipotential surface."

It is to be understood that the invention as here described is not limited to the details 105 of construction disclosed and shown and that these may be varied widely without departing from the spirit of the invention as defined by the claims.

I claim:

1. In a non-grounded electric transmission line, a closed metallic chamber, a generator of electric energy in said chamber, a receiving instrument in the chamber, both said generator and said instrument being suitably insulated from the metallic chamber, an insulated lead from one pole of said generator connecting with the corresponding pole of said instrument, and other leads connecting the other poles of the generator and the instrument respectively with the metallic chamber, substantially as set forth. 110 115 120

2. In a non-grounded electric transmission line, a closed metallic chamber, a generator of electric energy in said chamber suitably 125 insulated therefrom, a metallic extension from said chamber, a receiving instrument suitably insulated in said metallic extension, an insulated lead from one pole of said generator to the corresponding pole of the in- 130

strument, and return leads from the other poles of said generator and instrument respectively connecting with the metallic walls of the chamber and its extension.

- 5 3. In a non-grounded electric transmission line, a closed metallic chamber, a substantially closed metallic extension on said chamber, an insulated generator of electric energy in said chamber, external means for actuating the generator having suitably insulated driving connection therewith, a vacuum tube suitably insulated in said metallic extension, an insulated lead connecting corresponding poles of the generator and the vacuum tube, and return leads connecting the other poles of the generator and the vacuum tube respec-

tively with the walls of the chamber and the metallic extension, substantially as set forth.

4. An apparatus of the class described having an external, equipotential surface, an 20 electric transmission line enclosed in the apparatus and suitably insulated from the walls thereof and comprising a generator, a receiving instrument and a conductor between corresponding poles of the generator 25 and the instrument, the walls of the apparatus forming the return lead between the other poles of the instrument and the generator, substantially as set forth.

In testimony whereof I affix my signature.

LOUIS H. CROOK.
